ARTHUR GOHMANN, OF STETTIN, GERMANY, ASSIGNOR TO STETTINER CHAMOTTE-FAERIK ACTIEN-GESELLSCHAFT VORM. DIDIER, OF STETTIN, GERMANY, A CORPORATION OF GERMANY.

DEVICE FOR EMPTYING UPRIGHT COKING-CHAMBERS.

1,095,725.

Specification of Letters Patent.

Patented May 5, 1914.

Application filed January 17, 1913. Serial No. 742,548.

To all whom it may concern:

Be it known that I, ARTHUR GOHMANN, a subject of the German Emperor, and resident of Stettin, Germany, have invented certain new and useful Improvements in Devices for Emptying Upright Coking-Chambers, of which the following is a specification.

My invention relates to devices for emptying upright chambers of coke ovens or other apparatus in which the material undergoing treatment is discharged, at a certain state of the operation, from the lower ends of the chambers containing it.

According to the usual procedure, upright coking chambers are emptied by means of two cars arranged to travel under the oven, one of said cars being provided with a device for raising and lowering the bottoms used for closing the coking chambers, while the other car has a platform for receiving the coke discharged from the several chambers. Hitherto, the emptying operation was begun by withdrawing the bolts or latches serving to lock the bottom to the oven, and then the bottom was lowered a certain distance by means of the device provided for this purpose on one of the cars. Thereupon this car, or an auxiliary car traveling upon it and carrying the chamber bottom, was moved along under the oven, together with the coke-receiving car located adjacent to the first-named car. The chamber bottom was thus carried horizontally away from the coke column resting on it, and the platform of the coke-receiving car was brought under the coke column. A stationary retaining plate kept the coke column from following the movement of the cars, and thus the column was caused to collapse, the coke pieces falling on the platform of the coke-receiving car.

The customary procedure described above is objectionable on account of the exceedingly great friction arising between the heavy coke column and the chamber bottom as the latter is moved from under the coke column. Considerable power is therefore required to carry the chamber bottom away

from the coke column horizontally. Another drawback of the old procedure is that a relatively considerable time is required for emptying the coke chambers, since the bottom must first be moved downward by one device and then laterally in a horizontal direction, by another device.

According to my present invention, the bottom is first moved downward a certain distance, say in the manner customary hitherto, and then tilted downward so that the coke column discharged from the chamber will drop on the coke-receiving car. With this procedure, the emptying of the chamber takes place rapidly and requires relatively little power, in view of the fact that the tilting of the bottom for the purpose of dumping the coke on the coke-receiving car, dispenses with the necessity of moving the two cars at the time the coke is discharged, and furthermore, the bodily lowering of the bottom and its tilting movement can be accomplished in a single step of the operation, by moving the device (carried by one of the cars) which moves the bottom into and out of engagement with the oven.

Another advantage of my invention is that the upper surface of the bottom, on which the coke column rests, is much less subject to wear than with the procedure employed heretofore.

The quicker emptying of the chamber obtained with my invention is further advantageous in that the emptied chamber remains open at its lower end for a shorter time than hitherto and can therefore be put in operation again more rapidly. Any shortening of the interval during which the lower end of the chamber remains open is conducive to a more economical operation of the oven, for the reason that the efficiency of the oven (the output per 24 hours) is increased and the heat losses due to radiation are diminished.

According to my invention the time during which the emptied chamber remains open can be shortened still more by providing the car which carries the device for lowering the chamber bottom, with an addi-

tional device for raising and lowering an auxiliary bottom. Before the bottom of the chamber to be emptied is lowered, the auxiliary bottom may be prepared for being fitted to said chamber, that is to say, its joint surfaces may be provided with a suitable luting or packing material, such as clay, etc. After the bottom of the chamber to be emptied has been moved downward bodily and then tilted downward, to throw the coke on the coke-receiving car, the latter is moved away and simultaneously the car provided with the lifting and lowering devices is moved a short distance, so that the second of these devices, with the new (auxiliary) bottom will come directly beneath the emptied chamber. This new bottom may then be moved upward and applied to the emptied chamber by means of the second lifting and lowering device, so that after locking or latching the new bottom the chamber is again ready for operation.

One manner of carrying out my invention is illustrated in the accompanying drawings, in which—

Figure 1 is a side elevation, with parts in section on the line A—B of Fig. 2; Fig. 2 is a vertical section on line C—D of Fig. 1; Fig. 3 is a plan view of the car carrying the lifting and lowering devices, and also shows a portion of the coke-receiving car, the two cars, for the sake of clearness, being represented as moved apart slightly; Fig. 4 is a horizontal section through part of the car provided with the lifting and lowering devices, taken on the line E—F of Fig. 1; Figs. 5, 6 and 7 are vertical sections illustrating three different positions of an auxiliary car mounted to travel on the car shown at the left in Fig. 1.

In Fig. 1, the upright coking chambers 1 of the oven 3 supported on beams 2, are arranged in a set or bench, and are normally closed at their lower ends by means of plugs 4 or bottoms 4 of well-known character, these bottoms being held in the closed position by means of locking or latching devices well known in the art and therefore not illustrated in the drawings.

Viewed in horizontal section, the chambers 1 are of rectangular shape, as usual, the short side of the rectangle being shown in Fig. 1. Under the row or set of chambers 1 is arranged a track 5 at right angles to the long sides of the rectangular chambers 1, and on this track are adapted to travel the cars 6 and 7. The coke-receiving car 6 is provided with an inclined platform or container 9 supported by a frame work 8 and adapted to receive the coke discharged from one of the coking chambers 1. This car is provided with side walls 10 stationary in relation to the platform 9. At the upper end of the platform is arranged a plate 12

mounted to turn about a horizontal axis 11 65 and having its movement limited by the stops 13 and 14. At the lower end of the platform 9 a gate 15 is mounted to turn about a transverse horizontal axis 16, said gate being normally locked by means of any 70 suitable latching device (not shown). A toothed sector 17 is connected rigidly with the gate 15 to permit of swinging the gate by means of a pinion 18 meshing with said sector and provided with a crank. The 75 other car, 7, has a truck 19 provided with a horizontal platform 20, and carrying, by means of a frame work 23, another horizontal platform 22, located above the platform 20 and provided with a railing 21. 80

At that end of the car 7 which is shown at the right in Fig. 1, the truck 19 and frame 23 carry two vertical hydraulic cylinders (Fig. 2), the axes of which lie in a plane which is transverse to the track 5 and therefore parallel to the long sides of the rectangular coking chambers. The piston 25 of each cylinder 24 is provided at its upper end with a head 26 to which a frame 27 is secured. The lower surface of each 90 bottom 4 is provided with ribs 4^a rounded at their ends and adapted to rest on said frame 27 at the time the bottom 4 is lowered. At the ends of the frame 27 are secured downwardly extending, vertical rods 28 95 movable in guides 29 of the frame 23. The lower ends of the guide rods 28 are connected by a cross head 30 movable on the corresponding cylinder 24. The car 7 also carries another pair of hydraulic cylinders 100 31, similar in construction to the hydraulic cylinders 24, and arranged at that end of the car which is shown at the left in Fig. 1. Each of the cylinders 31 has a hydraulic piston 32 carrying at its upper end a head 105 34 connected with a frame 33. At the ends of the frame 33 are secured downwardly extending vertical rods 35 mounted to slide in guides 36 of the frame work 23 and connected at their lower ends by cross heads 37 110 115 movable on the respective cylinders 31. The pistons 32 ordinarily carry an auxiliary bottom 38 of the same construction as the bottom 4 and resting on the frame 33 by means of ribs 38^a corresponding to the ribs 4^a.

Each of the pairs of cylinders 24 and 31 is connected with a pipe 39 and 40 respectively for supplying water under pressure, the passage of water to said pipes from a supply pipe 43 being controlled by a cock or valve 42 actuated by a handle 41. When brought into a certain position, this cock connects the pipes 39 and 40 with a drain pipe 44. By properly manipulating the 120 cock 42, one or the other pair of cylinders 24 and 31 may be connected first with the supply pipe 43 so as to raise the pistons 25

or 32, and then with the drain pipe 44, to allow said pistons to return to their lower position. The cock 42 is so constructed that the two pairs of cylinders may be connected successively with the supply pipe 43, and also successively with the drain pipe 44.

The upper platform 22 of the car 7 carries a track 45 parallel with the main track 5. On this track 45 is adapted to run an auxiliary car 46 having a frame 47 mounted on short alining transverse shafts 48 journaled in brackets 49 of the auxiliary car. Normally, the carrying frame 47 is in the inclined position illustrated by Fig. 1, the portion of the frame to the right of the shaft 48 resting on stops 50 secured to the brackets 49. At the left-hand end of the frame 47 are secured two cross bars 51 each having at its upper end a horizontal pin 53 on which an angular arm 54 is mounted to turn. The arms 54 are adapted to receive the bottom 4 in the manner described below, and each of said arms is provided at its free end with a lug 55 and with a roller 56 which during the downward tilting of the arm travels on a horizontal guide 57 secured to the rods 28 of the adjacent piston 25. The roller 56 and its guide 57 are so arranged that with the auxiliary car 46 in the extreme right-hand position (Fig. 1) the roller 56 will be slightly to one side of the path of said guide, and at the moment the bottom 4 is caught by the receiving arms 54 as described below, the guide 57 will be slightly below the roller 56. With each of the arms 54 is connected a lever 59 provided with a counterweight 58, the downward movement of each lever being limited by a stop 60 on the corresponding bar 51. Each bar 51 carries a toothed sector 61 in mesh with a pinion 62. The two pinions 62 (Fig. 2) are secured to the same shaft 63 journaled in brackets 64 of the auxiliary car 46. One end of the shaft 63 is provided with an operating crank 65, the other end carries a ratchet wheel 66 engaged by a pawl 67 pivoted to one of the brackets 64. This pawl prevents any accidental downward movement of that end of the frame 47 which is shown at the left in Fig. 1, said end being provided with the toothed sectors 61 and the receiving device or carrier 54, 59.

The two cars 6 and 7 are propelled by separate electromotors 68 and 69 respectively, connected with one of the car axles by suitable gearing and controlled from the driver's stand of the respective car.

The operation of the above-described apparatus is as follows: When one of the coking chambers 1 is to be emptied, the car 7 is wheeled to such a position under the oven (see Fig. 1) that the pistons 25 will be directly below the oven chamber to be emptied. The auxiliary car 46 is also brought to the

position shown in Fig. 1. The plate 12 is then swung to the position indicated by dotted lines, and the car 6 is brought closely against the car 7 so that the upper end of the inclined platform 9 will be adjacent to the pistons 25. The plate 12 is then swung down into the position shown by solid lines, so as to rest against the ends of the arms 54. Thereupon the pistons 25 are caused to move upward until the frames 27 engage the lower surface of the bottom 4 of the coking chamber to be emptied. The bolts or other devices serving to lock the bottom 4 having been released, the pistons 25 are allowed to move downward, carrying with them the frame 27 and the chamber bottom 4 together with the coke column resting thereon, as shown in Fig. 1.

The bottom 4 is at first moved bodily downward in a vertical direction, until it comes to rest on the horizontal members of the receiving arms 54, as shown in Fig. 1. The downward movement of the pistons 25 however is not arrested at this point, but continues without interruption, whereupon the weight of the bottom 4 will cause the arms 54 to swing downward a short distance. This lost motion, as it were, of the arms 54, brings the rollers 56 against the upper surfaces of the horizontal guides 57 connected with the pistons 25. During the further downward movement of the pistons, the rollers 56 rest and travel upon the said guides 57. At this juncture therefore, the bottom 4 can no longer move bodily downward vertically in unison with the pistons 25, since the receiving arms 54 act as levers swinging about the axes of the rollers 56 and thus lifting the bottom 4 from the frames 27, the lugs 55 preventing the bottom 4 from sliding off the arms 54. The consequence is that during the further downward movement of the pistons 25 the bottom 4 is swung or tilted downward until it comes to rest against the inclined frame 47 as shown in Fig. 5. At the same time, the plate 12 drops against the stop 14 and thus takes a position in line with the platform 9. Fig. 5 also shows how the movement of the bottom 4 and of the plate 12 into the position just described causes the coke column to collapse, the coke sliding down upon the inclined platform 9 and being of course arrested at the lower end of it by the gate 15 which at the time is in the closed position shown in Fig. 1. The inclined position of the platform 9 causes the coke to be distributed uniformly upon it. The inclined position of the bottom 4 causes the coke to slide off the upper surface of said bottom readily and without any material friction. Thus no coke particles will remain upon the bottom 4, and it will not be necessary, as it was hitherto, to go to the trouble of cleaning

the upper surface of the bottom. The car 6 with the incandescent coke resting on the platform 9 is then brought to a quenching device of any suitable construction. Devices of this character being well known in the art, I have not deemed it necessary to show them in the drawings. After quenching, the coke may be withdrawn from the platform 9 by opening the gate 15, and then the car 6 is ready for the next operation.

Simultaneously with the transfer of the coke receiving car 6 to the quenching position, the car 7 carrying the bottoms 4 and 38 is moved a short distance in the same direction (that is to say, toward the right from the position shown in Fig. 5) into the position shown in Fig. 6 in which the pistons 32 of the auxiliary lifting device 31, 32 mounted on said car 7 will come directly below the chamber 1 which has just been emptied. Upon the frames 33 of the pistons 32 rests an auxiliary bottom 38 which has previously been prepared for closing the empty chamber, as by applying clay or other suitable material to the joints or contact surfaces of said auxiliary bottom. The pistons 32 are then raised so as to bring the auxiliary bottom 38 into or against the lower end of the emptied chamber 1, as shown in Fig. 6. The auxiliary bottom 38 is then secured to the oven by bolts or latches in any well-known or approved manner, and the chamber 1 is then ready to receive a new charge of coal. The pistons 32 are thereupon brought to their lowermost position in which the frames 33 take the position indicated by dotted lines in Fig. 6. The auxiliary car 46, together with the bottom 4 of the previously emptied chamber, which bottom rests on the inclined frame 47 on said car, is then moved from the position shown in full lines in Fig. 6 to the position indicated by dotted lines. The pawl 67 (Fig. 2) being thrown off the ratchet wheel 63, the crank 65 is turned to swing the frame 47 downward by the action of the pinions 62 on the toothed sectors 61, until such frame takes the horizontal position indicated by full lines in Fig. 7. Thereupon, the pistons 32 are moved upward, thus raising the bottom 4 and lifting it from the receiving arms 54 as indicated by dotted lines at the left-hand portion of Fig. 7. The bottom 4 having thus been removed from the auxiliary car 46, the latter (without the bottom 4) is wheeled back under the raised bottom 4 toward the right-hand end of the track 45 into the position indicated by dotted lines at the right-hand portion of Fig. 7. The arms 54 are then ready to receive the bottom 4 of the next chamber to be emptied. After the car 46 has been brought to this right-hand position, the pistons 32 are lowered until the bottom 4 is again in the po-

sition indicated by full lines in Fig. 7. This bottom 4 may then be used for closing the chamber 1 which is emptied next, in the same manner as has been described above with reference to the auxiliary bottom 38. For this purpose clay or other suitable packing material may be applied to the joint surfaces of this bottom 4 either before or after the chamber to be closed by said bottom has been emptied.

It will be obvious that with my invention the discharge of coke from the coking chambers can be effected very rapidly and with a relatively small expenditure of power, since at the time of discharging coke from one of the chambers, both the car 7 carrying the bottoms, and the coke receiving car 6 are stationary. The closing of the emptied chamber is also performed more quickly with my invention than hitherto, and this saving of time is obtained chiefly by the use of two operating devices, one of which, 24, 25, serves only to lower the bottom 4 which is to be removed from a coking chamber, while the other devices 31, 32, serves to raise the bottom (38 or 4) for closing the emptied coking chamber.

Various modifications may be made without departing from the nature of my invention as set forth in the appended claims.

I claim:

1. An apparatus for emptying upright chambers of coke ovens and other structures, comprising a car adapted to receive the material discharged from such chamber, and another car arranged to travel from chamber to chamber and adapted to receive the bottom employed for closing said chamber, said second car being provided with a device for first moving said bottom bodily in a vertical direction and then tilting said bottom. 100

2. An apparatus for emptying upright chambers of coke ovens and other structures having removable bottoms to close said chambers, comprising a car adapted to receive the material discharged from such chamber, and another car arranged to travel from chamber to chamber and provided with a vertically movable device for first moving a chamber bottom bodily in a vertical direction and then, as said device continues to move vertically downward, automatically tilting said bottom toward the first-named car to direct the material into the receiving car. 110

3. An apparatus for emptying upright chambers of coke ovens and other structures having removable bottoms to close said chambers, comprising a car arranged to travel from one chamber to another and adapted to receive the bottom employed for closing the chamber, a vertically movable device on said car, for first moving a chamber bottom downward bodily, and a device, like- 120
125

wise on the car, coöperating with the first-named device to automatically tilt said bottom as the downward movement of the first-named device continues.

5 4. An apparatus for emptying upright chambers of coke ovens and other structures having removable bottoms to close said chambers, comprising a car arranged to travel from one chamber to another and provided with a device for lowering a chamber bottom from its normal closed position, and with another device for raising another bottom to close the emptied chamber.

15 5. An apparatus for emptying upright chambers of coke ovens and other structures having removable bottoms to close said chambers, comprising a car adapted to receive the material discharged from such chamber, and another car provided with a 20 device for lowering a chamber bottom from its normal closing position, and with pivoted arms adapted to receive the bottom from said device and to tilt the bottom to cause the material to slide off from it into the 25 first-named car.

6. An apparatus for emptying upright chambers of coke ovens and other structures having removable bottoms to close said chambers, comprising a car adapted to receive the material discharged from such chamber, and another car provided with a device for lowering a chamber bottom from the normal closing position, horizontal guides connected with said device, and pivoted arms provided with rollers adapted to engage said guides, said arms being adapted to receive the bottom lowered by said device and to swing as the rollers travel along said guides, so as to tilt the bottom and discharge 40 the material into the first-named car.

7. An apparatus for emptying upright chambers of coke ovens and other structures having removable bottoms to close said chambers, comprising a car adapted to receive the material discharged from such chamber, and another car provided with a device for lowering a chamber bottom from its normal closing position, and with another device for raising another bottom to close 50 the emptied chamber.

8. An apparatus for emptying upright chambers of coke ovens and other structures having removable bottoms to close said chambers, comprising a car adapted to receive the material discharged from such chamber, and another car provided with a device for lowering a chamber bottom from its normal closing position, another device for raising another bottom to close the emptied chamber, and an auxiliary car mounted to travel on the second-named car and adapted to transfer a chamber bottom from said lowering device to said raising device.

9. An apparatus for emptying upright chambers of coke ovens and other structures having removable bottoms to close said chambers, comprising a car adapted to receive the material discharged from such chamber, and another car provided with a device for lowering a chamber bottom from its normal closing position, another device for raising another bottom to close the emptied chamber, and an auxiliary car mounted to travel on the second-named car, said auxiliary car being provided with pivoted arms adapted to receive the lowered bottom and to tilt it for the discharge of the material into the first-named car, and a frame movably connected with the auxiliary car and adapted to support the bottom upon the downward swinging of the said arms, said auxiliary car being arranged to travel on the second-named car from a point adjacent to the lowering device to a point adjacent to the raising device.

10. An apparatus for emptying upright chambers of coke ovens and other structures having removable bottoms to close said chambers, comprising a device movable toward and from the chamber to receive its bottom and lower such bottom bodily from the chamber, and pivoted arms held in the path of the bottom to receive it as it is lowered and to tilt it.

11. An apparatus for emptying upright chambers of coke ovens and other structures having removable bottoms to close said chambers, comprising a device movable toward and from the chamber to lower said bottom bodily, another device for raising a bottom to close the emptied chamber, and a traveler for carrying a bottom from a point adjacent to the first-named or lowering device to a point adjacent to the raising device.

12. An apparatus for emptying upright chambers of coke ovens and other structures having removable bottoms to close said chambers, comprising a lowering device for carrying such bottom bodily from the chamber, another device for raising a bottom to close the emptied chamber, and a traveler provided with a tilting carrier adapted to receive a bottom from the first-named or lowering device and to deliver such bottom to the said raising device.

13. An apparatus for emptying upright chambers of coke ovens and other structures having removable bottoms to close said chambers, comprising a car arranged to travel from one chamber to another and provided with a device for lowering a chamber bottom from its normal closing position, another device for raising another bottom to close the emptied chamber, and an auxiliary car mounted to travel on the first-named car.

and adapted to transfer a chamber bottom from said lowering device to said raising device.

14. An apparatus for emptying upright chambers of coke ovens and other structures having removable bottoms to close said chambers, comprising a car arranged to travel from one chamber to another and provided with a device for lowering a chamber bottom from its normal closing position, with another device for raising another bot-

tom to close the emptied chamber, and with means for transferring a chamber bottom from said lowering device to said raising device.

15

In testimony whereof I have signed this specification in the presence of two subscribing witnesses.

ARTHUR GOHMANN.
